UNITED STATES PATENT OFFICE.

HENRY A. WEIHMANN, OF PHILADELPHIA, PENNSYLVANIA.

DESIGN FOR A THIMBLE.

SPECIFICATION forming part of Design No. 20,590, dated March 17, 1891.

Application filed February 6, 1891. Serial No. 380,505. Term of patent 14 years.

To all whom it may concern:

Be it known that I, HENRY A. WEIHMANN, a citizen of the United States, residing in Philadelphia, in the county of Philadelphia and State of Pennsylvania, have invented and produced a new and original Design for Thimbles, of which the following is a specification, reference being had to the accompanying drawings, forming part thereof.

10 In the drawings, Figure 1 is an elevation of a thimble, showing my improved design. Fig. 2 is a cross-section of the thimble on line X-X, and Fig. 3 is a plan view indicating the metal composing the thimble laid out flat.

15 The crown part A of the thimble is made in the usual way, with depressions upon which the needle catches. The lower portion of the thimble B, or that adjacent to the orifice, is made of flat sides forming a polygon in

20 cross-section, as indicated in Fig. 2. This portion of the thimble is ornamented by smooth plane surfaces and depressed sur-

faces, as indicated in the various figures. The ornamentation upon the base of the thimble consists of the arched patterns D, terminating in the trefoils d, with the intermediate leaf-patterns E. The lower portion of the thimble is formed with a scalloped edge C.

The essential feature of the design lies in the polygonal shape of the lower portion, combined with the circular shape of the upper portion and with the ornamental work formed upon said lower portion, as described.

Having now described my new design, what I claim as new, and desire to secure by Letters Patent, is—

The design for thimbles, substantially as herein described and shown.

In testimony of which invention I have hereunto set my hand.

HENRY A. WEIHMANN.
